UNITED STATES PATENT OFFICE

152,531

DESIGN FOR A FABRIC

Marion R. Hamre, Oceanside, N. Y.

Application July 11, 1947, Serial No. 140,221

Term of patent 7 years

(Cl. D92—1)

To all whom it may concern:

Be it known that I, Marion R. Hamre, a citizen of the United States of America, residing in the city of Oceanside, county of Nassau, and State of New York, have invented a new, original, and ornamental Design for a Fabric, of which the following is a specification, reference being had to the accompanying drawing, forming a part thereof.

The drawing is a front view of the fabric, showing my design;

The broken lines outline a design unit which unit is repeated over the fabric in regular succession as indicated by the extensions beyond the unit boundaries.

I claim:

The ornamental design for a fabric, as shown and described.

MARION R. HAMRE.
